UNITED STATES PATENT OFFICE.

PHILIP A. BECKER, OF NEW YORK, N. Y.

KNOCKDOWN CASE.

974,739.

Specification of Letters Patent.

Patented Nov. 1, 1910.

Application filed May 22, 1909. Serial No. 497,671.

To all whom it may concern:

Be it known that I, PHILIP A. BECKER, a citizen of the United States, and a resident of New York, borough of Brooklyn, county of Kings, and State of New York, have invented certain new and useful Improvements in Knockdown Cases, of which the following is a full, clear, and exact description.

10 This invention relates more particularly to a knock-down display case.

The primary object of the invention is to provide a simple and efficient case having a plurality of members which are constructed to be detachably held together so that when assembled for use a maximum amount of space and show surface is provided, and which, when knocked down, may be made to assume a form which will be 20 convenient for shipping or transportation purposes, thus doing away with an expensive and bulky box when the case is to be transported.

Another object of the invention is to provide an attractive case which may be made partly of wood and partly of glass, or substantially all of glass with a metallic frame, and to so construct the parts that the same may be readily assembled or knocked down.

30 A further object of the invention is to provide simple and efficient means for holding the glass part to the frame portions of the casing, and to provide a case which may be used for advertising or other purposes 35 and for displaying various kinds and character of goods.

With these and other objects in view, the invention will be hereinafter more particularly described with reference to the accompanying drawings, which form a part of this specification, and will then be pointed out in the claims at the end of the description.

40 In the drawings, Figure 1 is a perspective view of one form of casing embodying my invention, showing the same in position for use. Fig. 2 is a perspective view of the case taken apart or knocked down, showing the same ready for packing or for transportation purposes. Fig. 3 is a vertical longitudinal section. Fig. 4 is an enlarged fragmentary section of the upper portion of the top member of the device. Fig. 5 is an enlarged transverse section taken on the line 50 V—V of Fig. 3, showing how the two members of the casing are held together. Fig. 6

is a fragmentary side elevation with the tops or covers of the members removed. Fig. 7 is a plan view of the interior of one of the covers, showing how the glass may be held within the frame. Fig. 8 shows how a case may be made or built up of three sections or members. Fig. 9 is a fragmentary side elevation of a case in which the members are made of glass and metallic frames, 65 and shows another means for holding the members detachably together; and Fig. 10 is an enlarged transverse section taken on the line X—X of Fig. 9.

The case, in Figs. 1 to 7, has two members 70 10 and 11. The member 10 is substantially triangular in cross-section and has its rear wall 12 and side walls 13 of wood, and the sides 13 are so shaped that the top or cover 14 will stand at an inclination when placed 75 in position. This top 14 has a glass part or plate 15 and a metallic frame 16 for holding the plate 15 and serves as a marginal wall and fastening means for the top. The frame 16 has marginal flanges 17 to fit the sides and top 80 edges of the member 10, and the lower flange of the frame is adapted to fit under a ledge 18 formed as a part of a transversely-extending bar 19 serving as a top for the member 11 but held to the member 10. The upper marginal flange of the cover 14 is provided with 85 two clips or strips 20 arranged near the opposite sides of the cover, and said clips are adapted to fit over and clamp the upper edge of the rear wall 12 so as to properly 90 hold the cover detachably to the member 10.

The member 11 is substantially box-shaped in form and has a rear wall 20^a adapted to be in alinement with the rear wall 12 of the member 10, and has a bottom 95 21, a front wall 22, and side walls 23. The front wall 22 is somewhat shorter than the rear wall 20^a and the sides 23 are angularly formed, and said member is provided with a cover or top 24 which has one end extending 100 adjacent to the lower edge of the cover 14 of the member 10. This cover 24 has a metallic frame 25 and a glass plate 26 held in the frame, and said frame has marginal walls 27 which are adapted to fit about the 105 side walls 23 and the front wall 22. One wall of the frame 25, as 28, is adapted to engage notches or grooves 29 in the side walls 23 so as to hold the top detachably to the member 11. It will thus be seen that by 110 forming the sides angularly, the transversely-extending bar or part 19 forms a

bottom for the member 10 and a top for one part of the member 11, and the cover 24 closes the upper part of the box-like member 11 and is made to incline so that the goods within the same, which is intended to be displayed, may be readily seen.

To detachably hold the members 10 and 11 together, I provide grooves 30 in the outer edges of the bar 19 and adapted to enter the grooves 30 are ribs or tongues 31 which are attached to or formed as a part of the side walls 23 of the member 11, as best shown in Figs. 3 and 5. It will be seen that by removing the cover 24 from the member 11, the member 10 may be detached from the member 11, and by reason of the triangular construction of the member 10 and the angular form of the upper portion of the member 11, the members of the case when knocked down may be positioned as shown in Fig. 2, to form a convenient package for packing or for other purposes.

The glass may be held in the frame of the cover in any suitable way, and the cover 25 may be used for various purposes. As shown, the frame of both the covers 14 and 24 have small strips of metal 32, Figs. 3 and 7, and these strips or devices may be soldered or otherwise held to the frame of the cover and are adapted to be bent over so as to hold the glass plate properly within the frame. By this construction simple and efficient means are provided for holding the glass to the metallic frame.

35 In Fig. 8, the casing may comprise the members 33, 34 and 35. The intermediate member 34 may be detachably joined to the other members substantially as shown in Fig. 5, or otherwise, and said intermediate 40 member may have a curved forward portion which is adapted to be closed by a cover 36 which may be constructed substantially the same as the covers 14 or 24; and while three members are shown in this figure, any desired number or form of members may be provided to form a built-up case which may be so constructed that it may be knocked down.

In Figs. 9 and 10, the members 37 and 38 50 may be substantially the same as the members 10 and 11 so far as shape is concerned, but in this case the sides and front are of glass with metallic frames for holding the same. Here the member 10 may be provided 55 with a part 39 on each side thereof having an extended portion 40 in the form of a bolt or pin, which is adapted to fit into a sleeve 41 which is held to a transversely-extending bar 42 at each end thereof. This 60 bar 42 is carried by the member 37 and has a frame 43 and a glass plate 44 held in the frame, and said plate is adapted to form the top of the lower member 38, though there may be more than two members if desired. The sleeve 41 and device 40 entering

the same forms a ready means whereby the members of the case may be detachably held together.

From the foregoing it will be seen that a simple and efficient device is provided which 70 is adapted particularly for the display of goods for advertising or for other purposes; that said case is simple in construction and may be readily and cheaply made so as to adapt it for the purpose intended; that said 75 casing may be made attractive in appearance and either of glass or metal or a combination of glass, metal and wood or other material; that simple and efficient means is provided whereby the members may be detachably held together to be readily placed 80 in position to display the goods or to be knocked down for transportation purposes; and that said members may be so formed that when the case is knocked down the said 85 member will form substantially a rectangular package convenient to be placed in a packing or other box.

Having thus described my invention, I claim as new and desire to secure by Letters Patent:—

1. In a display case, a cover having a metallic frame substantially L-shaped in cross section, a glass plate fitting said frame and members adapted to engage both surfaces and the edge portion of said plate, said members being secured to said frame.

2. In a display case, a cover having a metallic frame substantially L-shaped in cross section, a glass plate fitting within 100 said frame, said frame being provided with an off-set portion adapted to engage said plate and members adapted to engage both surfaces and the edge portion of said plate, said members being secured to said frame. 105

3. In a display case, a cover having a metallic frame, a glass plate fitting within said frame the edges of said frame partly in-casing the edge of said glass plate and U-shaped members secured to the inner surface of said frame for securing the glass within the frame. 110

4. A display case comprising a box-like member having tongues formed at the upper edge thereof, an inclined portion, a cover 115 having a glass plate formed as a part thereof and a frame in which the plate is held, said box-like member of the casing having grooves along its upper edges to adapt the frame of the top to enter the same and hold 120 the top to the casing, and a substantially triangular member having its bottom formed of a transversely-extending bar having grooves to slide along the tongues to adapt said member to be readily detached 125 from the box-like member, said triangular member being provided with a cover having a metallic frame and a glass portion held to the frame, said frame being provided with marginal walls adapted to engage a 130

part of the casing of the triangular member and having cleats adapted to engage the upper edge thereof to hold the cover to said member.

- 5 5. A display case having a box-like member, a substantially triangular member, said triangular member being provided with a cover or top having a metallic frame and a glass portion held to the frame, said frame 10 being provided with marginal walls adapted to engage a part of the casing of the triangular member and having cleats adapted to engage the upper edge thereof to hold the cover to said member.
- 15 6. A display case comprising a box-like member having an inclined portion, a cover having a glass plate formed as a part thereof and a frame in which the plate is held, a substantially triangular member provided 20 with a cover having a metallic frame and a glass portion held to the frame, said frame being provided with marginal walls adapted to engage a part of the casing of the triangular member and having cleats adapted 25 to engage the upper edge thereof to hold

the cover to said member, and means for detachably holding the members together.

7. A display case comprising a box-like member having tongues formed at the upper edge thereof, an inclined portion, a cover, 30 said box-like member of the casing having grooves along its upper edges to adapt the frame of the top to enter the same and hold the cover to the casing, and a substantially triangular member having its bottom 35 formed with grooves so as to slide along the tongues to adapt said member to be readily detached from the box-like member, said triangular member being provided with a cover having marginal walls adapted to engage a part of the casing of the triangular member and having cleats adapted to engage the upper edge thereof to hold the cover to said member.

This specification signed and witnessed 45
this 21st day of May A. D. 1909.
